I. H. SHAFER

MONEY RECEPACLE

Filed July 24, 1926

Inventor

Innes Holt Shafer

By *George C. Grant*

Attorney

UNITED STATES PATENT OFFICE.

INNES HOLT SHAFER, OF RICHMOND, VIRGINIA.

MONEY RECEPACLE.

Application filed July 24, 1926. Serial No. 124,624.

My invention consists in new and useful improvements in money receptacles, and relates particularly to that class of receptacles adapted to be used as children's budget boxes, its object being to provide a box arranged to take care of all money received by a child from whatever source derived, whether it be allowance from parents or guardians, gifts, or earnings in various ways. For the sake of regularity and economy, the plan is arranged upon the basis of weekly receipts.

A further object of my invention is to provide a budget box which will be attractive and practical for children of five years through the 'teen age.

With the above and further objects in view which will appear as the description proceeds, the invention consists in the novel features herein set forth, illustrated in the accompanying drawing, and more particularly pointed out in the appended claim.

Referring to the drawing, in which numerals of like character designate similar parts throughout:

Figure 1 is a perspective view of the preferred form of my invention showing the main receptacle with the top opened.

Figure 2 is a cross section looking from one end of the main receptacle and showing one of the smaller receptacles inserted therein.

In the drawing, 1 designates the main receptacle which consists of a rectangular box composed of any suitable material, and preferably having a lid or top 2 hinged to one of the longitudinal edges thereof. 3 represents a transparent window inserted in the front wall 4 of said receptacle 1. The receptacle 1 is adapted to receive a plurality of smaller receptacles 5, 6, 7, 8 and 9 which may be removed therefrom, each of which is provided with a slotted removable lid 10, whereby coins may be inserted. Each of said smaller receptacles is provided on its front wall with a symbolic figure which may be of any particular design, the preferred symbols being shown in Figure 1 of the drawing. In this figure, the small receptacle 5 bears the representation of a bee hive, symbolizing thrift, receptacle 6, the representation of a cross, symbolizing God; recep-

tacle 7, the representation of an owl, generally known as symbolizing wisdom, in this particular case wisdom of saving; receptacle 8, the representation of a blue bird, symbolizing happiness; and receptacle 9, the representation of the sun, symbolizing sunshine brought into the lives of others. These small receptacles are inserted in the main receptacle in such a position that said symbols may be readily viewed through the transparent window 3.

On the inner surface of the lid or cover 2, above each of the smaller receptacles, I provide a chart which classifies said smaller receptacles, for instance over the receptacle 5 appears the title, Earning box; over the receptacle 6, God's box; over the receptacle 7, Savings box; over the receptacle 8, Spending box; and over the receptacle 9, Giving box.

The use of my device is as follows: All money received during the week is deposited in the earning box, symbolized by the busy bee, and at the end of the week it is divided among the other boxes as follows: The first portion set aside for definite use is for God, and is put into God's box, symbolized by the cross; the next portion to be set aside is for the Savings box, symbolized by the wise old owl, the amount to be put into this box being suggested by the parent and adhered to by the child, and when the amount in the box reaches the sum of, we will say, one dollar (\$1.00), a bank account should be opened in his name and regularly added to as the accumulation in the little box justifies. The next portion is inserted in the Spending box, symbolized by the blue bird, and is for the child himself; the last portion is to be put into the Giving box, symbolized by the sun, from which the child makes gifts to others. Thus each week though the child may have but a small amount, each box would receive a reasonable portion for each purpose.

From the foregoing, it is believed that my invention may be clearly understood without further description, it being borne in mind that numerous changes may be made in the details of construction without departing from the spirit of the invention as disclosed in the appended claim, for instance, the Spending box may be separately budgeted,

a larger number of small receptacles may be employed in the main receptacle, or different symbols and legends may be used with equal effect.

5 What I claim and desire to secure by Letters Patent is:

A budget box comprising a main receptacle having a lid hinged thereto, and a transparent window in one wall thereof,
10 a plurality of smaller receptacles adapted to

be inserted in said main receptacle, each of said small receptacles being provided with a slotted cover and having a symbolic picture on one wall thereof adapted to be viewed through said window, said main lid being 15 provided on its inner surface with a descriptive legend adjacent each small receptacle and corresponding to the picture thereon.

In testimony whereof I affix my signature.

INNES HOLT SHAFER.
